UNITED STATES PATENT OFFICE

162,060

ASH TRAY

Ellis F. Nelson, Everett, Mass., assignor to New Can Company, Inc., Malden, Mass., a corporation of Massachusetts

Application January 13, 1950, Serial No. 7,232

Term of patent 7 years

(Cl. D85—2)

To all whom it may concern:

Be it known that I, Ellis F. Nelson, a citizen of the United States, residing at Everett, in the county of Middlesex, in the Commonwealth of Massachusetts, have invented a new, original, and ornamental Design for an Ash Tray, of which the following is a specification, reference being had to the accompanying drawing, forming a part hereof.

Fig. 1 is a top plan view of an ash tray showing my new design; Fig. 2 is a side elevational view thereof; and Fig. 3 is a front elevational view thereof.

I claim:

The ornamental design for an ash tray, as shown.

ELLIS F. NELSON.
